UNITED STATES PATENT OFFICE.

VINCENT A. MENUEZ, OF MICHIGAN CITY, INDIANA.

FOLDING TABLE.

SPECIFICATION forming part of Letters Patent No. 281,281, dated July 17, 1883.

Application filed September 7, 1882. (No model.)

To all whom it may concern:

Be it known that I, VINCENT A. MENUEZ, a citizen of the United States, residing at Michigan City, in the county of La Porte and State 5 of Indiana, have invented certain new and useful Improvements in Folding Tables, of which the following is a specification, reference being had therein to the accompanying drawings.

My invention consists in the construction 10 and combination of parts, as hereinafter more fully described, and pointed out in the claims.

Referring to the drawings, Figure 1 shows an elevation of my improvement; Fig. 2, an inverted plan view, taken on the line $x-x$ of 15 Fig. 1; and Fig. 3 is an inverted view of the legs and leaves folded together.

Like letters of reference indicate like parts in each of the figures.

In the drawings, A is a narrow rigid top, in 20 the exact center of which is permanently secured a rigid upper cross-piece, B, to which legs b , having the bar b' cut away on its lower edge, are mortised or otherwise suitably secured. The cross-piece B is cut away on its 25 upper edge to form a space between it and the top A for the passage of the cross-piece C, having legs c and bar c' . The cross-piece C and bar c' are cut away in the center, as shown in Fig. 3, to permit the ends to fold against 30 the opposite sides of the cross-pieces B and b' . The central portions of the cross-pieces C c' of the swinging frames are of the same width as the central part of the table, while their ends are cut away on opposite sides, whereby they 35 are made to fit closely against the cross-pieces of the stationary frame when closed, while their outer edges are flush with the edges of the central part of the table. The leaves a of the table are hinged to the rigid top A and are 40 provided with cleats or stops a' .

By my construction the part B is secured in the center of the table, leaving space for the convenient attachment of the hinges, enabling the table to be folded in a compact form for 45 shipment or storage. The cross-pieces B C and bars $b' c'$ are pivoted together, as clearly shown in the drawings.

All the parts of my table except the top being cut from boards of uniform thickness, can

be sold at a price that will bring it within 50 the reach of all and manufactured by unskilled workmen. The top may also be made of the same thickness, or of lighter material, as desired.

I am aware that the rigid top, hinged leaves, 55 and folding legs are not broadly new.

What I claim, and desire to secure by Letters Patent, is—

1. A table-top consisting of the narrow part A and parts a hinged thereto, and the frame 60 composed of the upper cross-piece, B, rigidly secured to the part A of the table-top, upon its longitudinal center, legs b , and the cross-piece b' , the said cross-pieces being of uniform thickness throughout, in combination with 65 the movable frame consisting of the cross-pieces C and c' , and legs c , the said cross-pieces having a central portion of the same width as the part A of the table-top, and being cut away at each end on opposite sides, 70 as described, and pivoted to the centers of the cross-pieces of the stationary frame through the broad central portions, substantially as and for the purposes set forth.

2. In a folding table, substantially such as 75 herein shown and described, a top consisting of a narrow central piece and two leaves hinged thereto, a cross-piece having two legs connected by a cross-piece at their lower ends, rigidly secured to the longitudinal center of 80 the central part of the table, in combination with a swinging cross-piece having two legs, also connected at their lower ends by a cross-piece, the cross-pieces of the swinging frame extending above and below the cross-pieces 85 of the stationary frame, and being pivoted to the same, substantially as and for the purpose set forth.

3. In a folding table, a top consisting of a narrow central piece and two leaves hinged 90 thereto, a cross-piece having two legs connected by a cross-piece at their lower ends, rigidly secured to the longitudinal center of the central part of the table, in combination with a swinging cross-piece having two legs, 95 also connected at their lower ends by a cross-piece, the central portion of both of the swinging cross-pieces being of the same width as the

central part of the table, the said cross-pieces being cut away at their ends on opposite sides, as described, whereby they are made to fit closely against the cross-pieces of the stationary frame when closed, while their outer edges will be flush with the edges of the central part of the table, as and for the purposes set forth.

In testimony whereof I affix my signature in presence of two witnesses.

VINCENT A. MENUEZ.
